UNITED STATES PATENT OFFICE

ERNEST O. FREDERICKS, OF NEW YORK, N. Y., ASSIGNOR TO E. FREDERICKS, INC., OF NEW YORK, N. Y., A CORPORATION OF NEW YORK

HAIR DRIER

Application filed January 12, 1929. Serial No. 332,215.

This invention relates to apparatus for treating the hair and scalp, and is an improvement upon the structure set forth in my pending application, Serial No. 153,300, and 5 is in part a continuation thereof.

It is an object of the invention to provide a device and apparatus of this character which may be utilized for the drying and treating of both hair and scalp, and the parts 10 of which are relatively few in number and rugged in construction to provide an economical apparatus capable of use over long periods of time and with freedom from mechanical difficulties.

15 It is a further object to provide an apparatus of such construction that the hair may be dried and treated in a minimum period of time, and in which such drying and treatment will be uniform in effect.

20 It is a still further object to provide an apparatus capable of being employed by an operator having no particular mechanical skill, and in the operation of which no difficulty will be experienced by the person utilizing the same.

25 Another object is that of providing a hair treating apparatus which may be readily shifted from place to place, and in which the nozzle may be caused to assume any desired 30 position, and will maintain such position until the operator desires to shift the same, the apparatus being so constructed as to remove or minimize the likelihood of damage to the apparatus or of injury to the person being treated or to the operator.

35 Still another object is to provide a readily accessible heating-unit that is readily-demountable as a unit, and comprises readily-detachable heating-coils.

40 Other objects of the invention will in part be obvious and will in part appear herein-after.

45 The invention accordingly comprises the features of construction and arrangement of parts, and the combination thereof, which will be exemplified in the construction hereinafter set forth and the scope of the application of which will be indicated in the claims.

50 For a fuller understanding of the nature

and objects of the invention, reference should be had to the following detailed description taken in connection with the accompanying drawings, in which:

Fig. 1 is a perspective view of a preferred 55 form of the apparatus, showing the nozzle member as swung back on its hinge so as to rest on the fan-casing, thus exposing the outer end of the heating-unit;

Fig. 2 is a side view of the motor-casing 60 and a vertical section of the fan-casing; showing the fan in position upon the end of the motor-shaft;

Fig. 3 is a vertical section through the fan-casing and fan, taken at right angles to the 65 view in Fig. 2;

Fig. 4 is an elevation of the outer face of the fan-casing;

Fig. 5 is a plan looking down on the fan-casing, heating-section and nozzle-section; 70

Fig. 6, on a larger scale, is a longitudinal section through the heating-chamber, showing one side of the demountable heating-unit; and

Fig. 7 is a diagram indicating the switch- 75 control and the various circuits.

Referring to these drawings, Fig. 1 shows a pedestal mounted on castors and carrying a standard 10 that supports a motor-casing 11, which in turn supports all the rest of the 80 apparatus. A fan-casing 12, which may be of sheet-metal, is swiveled at the end of said motor-casing in such manner as to have rotary motion within a limited range of about 180 degrees. A cable 13 contains the main 85 electric leads that pass to the motor (not shown) and to the heating-unit. At 14 is indicated a circuit-controlling switch, preferably a three-point switch, the first movement of the switch closing a circuit through the motor, a further movement closing a circuit through a pair of heating-coils, and a still further movement of the switch closing a circuit through another pair of heating-coils, as indicated in Fig. 7. As seen in Fig. 90 95 3, the main portion of the fan-casing is substantially circular, and a funnel-like throat leads tangentially therefrom towards a vent 15, which funnel is defined on one side by a straight (tangential) wall 16, and on the 100

opposite side by a convexly-curving wall 17, so that the air-current set up by a rotary fan (within the casing 12) will encounter no sudden constriction or buffer or re-entrant wall which would tend to produce noise. From said vent 15 the air-current passes through a heating-section or chamber 18, which is demountably telescoped over the vent. To the outer end of this section 18 a nozzle-section 19 is hinged at 20, so it can be folded back to rest upon the fan-casing, thus exposing the outer end of the demountable heating-unit, as indicated in Fig. 1.

In addition to the funnel-like and smooth-walled throat leading from the fan-casing, it will be observed that the cross-section of the air-conduit becomes somewhat larger within the heating-chamber and thereafter continues smoothly with little, if any, change in cross-section until at the outer end of the nozzle, where a constricting annulus 21 is provided, as seen in Fig. 5, for properly delivering the blast or current of heated air.

Referring now to Fig. 2, that end of the motor-casing which is adjacent the fan-casing has a cylindrical shoulder 22 which provides a circular reduction; and in the adjacent face of the fan-casing is provided a circular opening of such diameter as to take freely over this shoulder. At the same end of the motor-casing is a heavy bearing 23 through which a rotary fan-shaft 24 (from the motor, not shown) protrudes into the fan-casing and carries a fan 25. A tension-disc 26 of resilient metal, and a frusto-conical shape and with a central opening, is applied over the shaft and with the outer margin of its concave face overlapping the margin around the aforesaid opening in the fan-casing, and bearing against the inner face of the casing; then a stout annulus 27 is applied over the shaft and forced against the crown of the tension-disc, and is secured to the heavy bearing 23 aforesaid, as by a plurality of bolts. This forcing of the annulus 27 against the crown of the tension-disc tends to flatten the latter, thus causing notches provided in the edge of the disc to engage corresponding lugs 28 provided on the inner face of the fan-casing, this compression thus placing the frusto-conical disc under stress, whereby the marginal notches of the latter are caused to straddle the lugs 26, and this disc itself is caused to bear frictionally upon the adjacent margin of the interior face of the fan-casing. As indicated in Fig. 2, the end of the motor-casing is provided with lugs, as 29, for engaging with corresponding projections 29' formed on the disc 26, to limit the rotary movement of the fan-casing and the disc to (say) 180 degrees, in order to prevent undue stretching of the circuit-wires which lead from the control switch 14 and into the heating-chamber 18.

By reason of this engagement of lugs 28,

any rotary movement imparted to the fan-casing is transmitted to the tension-disc. The tension-disc will have relative rotary movement with respect to members 23 and 27, which frictionally engage the crown-portion thereof; and for this reason and because the disc is under tension, the fan-casing (with sections 18 and 19 carried by it) will remain stationary in whatever position of rotary adjustment has been selected for directing the air-current from the nozzle towards the scalp and hair of the patron being treated, until an intentional shift of adjustment is effected.

In the outer face of the fan-casing is a large opening for the introduction and installation of the fan 25, and for the admission of air to the fan; preferably the opening and the main or circular portion of the fan-casing are eccentric with respect to the shaft 24. In such case, the fan can be installed by inserting two adjacent fan-tips into this opening and beneath that portion of the side-wall of the fan-casing which has the greatest overhang with respect to the opening; and then, upon shoving these fan-tips as far as they can go, the other fan-tips can readily be introduced and the hub of the fan can be applied over the motor-shaft and secured thereon.

After the fan has been installed, a plate 30 may be secured over the opening. This plate has a concentric arrangement of sector-shaped openings, which are preferably screened with wire gauze. This plate carries concentrically a revoluble cover 32 having a similar arrangement of free openings and controlled by a handle 33 located to operate over a dial. By shifting the position of this handle, the operator controls the amount of air drawn into the fan; and by means of this control, and the switching at 14, the volume and the temperature of the emitted air-current is regulated as desired.

Referring now to Fig. 6, 34 represents a bar of insulating-material, which is secured diametrically within the inner end of the heating-section 18, while the latter is removed from the fan-casing, as by means of screws passed from the exterior of section 18 into the ends of this bar. This bar is provided with three socket-members 35, each of conducting material. Two parallel metal rods 36 are secured to the end-portions of this bar, and project into the chamber and longitudinally thereof. This bar 34 and its rods and sockets are for removably mounting the demountable heating-unit, to be next described.

Referring still to Fig. 6, a plate 37 of insulating material is provided along its opposite side-edges with parallel tubes or sleeves 38—38 of metal, and from what is to be the inner end of the plate project three parallel contact-plugs 39, 40, 41, all of metal.

These sleeves are to take over the rods 36, and these contact-plugs are to enter the socket-members 35, presented by said bar 34. In electric connection with the middle plug 40 is a metal stud 42 whose two ends project from opposite faces of the plate; and in electric connection with each of the other two plugs (39 and 41) is a separate stud 43, one of them projecting from one face of the plate and the other from the opposite face. Two heating-coils 44 and 45, of crinkled wire or ribbon of high resistance, are disposed on one face of the plate, and one end of each coil is detachably connected, one to one end of the middle stud 42, and the other to the end of another stud 43; while the outer ends of these two coils are detachably connected to the ends of two other metal studs carried by the outer end of plate 37. On the opposite face of plate 37, two other like coils 46 and 47 are similarly disposed, and are detachably connected at their inner ends respectively to the middle stud 42 and to the third stud on the inner end of the plate, and at their outer ends respectively to a third and a fourth stud on the outer end of the plate. On the outer end of the plate is provided an electric connection between the outer ends of one of the coils (as 44) on one face of the plate and the outer end of one of the coils (as 46) on the opposite face; and a similar electric connection is provided between the outer ends of the other two coils, as 45 and 47. This plate 37 and its coils, that are individually demountable, and the other parts secured to the plate, constitute a heating-device, which is demountable as a unit. It is inserted into the heating-chamber 18, after the nozzle-section 19 has been swung back as indicated in Fig. 1, the sleeves and contact-plugs of plate 37 engaging the rods and socket-members of bar 34, and the unit is then secured in place by means of nuts screwed down upon the projecting threaded ends of the rods. Upon loosening these nuts, and withdrawing the plate, the heating-unit can be withdrawn and one or more of its coils can be removed and a substitute applied, or an entirely fresh unit can be substituted.

From the control switch at 14, a lead-wire 48 runs to the middle socket-member 35 (on bar 34) and is connected thereto. Two other wires 49 and 50, from the switch, are separately connected respectively to the other two socket-members. The course of the circuits may be traced by referring to Fig. 7, as follows: from the switch, through wire 48 to the middle socket and its double-ended stud 42, where the current divides, one branch going from one end of stud 42, through one pair of coils to a second socket member, and back through wire 49, and the other branch going from the other end of stud 42, through the other pair of coils, to the third socket-member, and back through wire 50; or vice-versa.

If desired, some additional electric device, such as an electric bulb 51 in a suitable mounting 52, can be utilized. This mounting may be a sleeve carrying the bulb and provided with two slide-contacts connected electrically therewith, for telescoped engagement with the outer end of the heating-section 18, after swinging the nozzle-section 19 back out of the way. For this purpose the return-wire 48 may be connected to the inner end of one of the rods 36 (on bar 34) as well as to the middle socket-member, and one of the two feed-wires (49 or 50) can be connected to the inner end of the other rod as well as to its own socket-member; so that the additional circuit will pass from the outer end of one rod 36, through a slide-contact and a suitable connection to the bulb, all carried by mounting 52, and will return through a similar connection and slide-contact to the outer end of the other rod.

Since certain changes may be made in the structures and arrangements described above, and different embodiments of the present invention can be made, without departing from the spirit thereof, it is intended that all matter contained in the foregoing description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

The invention having thus been fully described, what is claimed is:

1. In combination, in apparatus of the character indicated, a casing containing a motor and having a hub from which protrudes the shaft of the motor, a fan-casing enclosing a fan carried by said shaft and having one of its side-walls provided with a circular opening through which said hub projects, a lug located on the inner face of said side-wall and near said opening, a frusto-conical disc of resilient metal whose central or crown-portion has a circular hole into which the end of said hub extends, the marginal portion of said disc having a notch that straddles said lug, means tending to flatten said disc and coacting with said hub to clamp said crown-portion frictionally between them, and stops carried respectively by said hub and said disc and limiting the extent of rotary movement of the latter.

2. In combination, in apparatus of the character indicated, a casing containing a motor and having a hub from which protrudes the shaft of the motor, a fan-casing enclosing a fan carried by said shaft and having one of its side-walls provided with a circular opening through which said hub projects, a lug located on the inner face of said side-

wall and near said opening, a frusto-conical disc of resilient metal whose central or crown-portion has a circular hole into which the end of said hub extends, the marginal portion of said disc having a notch that straddles said lug, and means tending to flatten said disc and coacting with said hub to clamp said crown-portion frictionally between them.

3. In combination, in apparatus of the character indicated, a casing containing a motor and having a hub from which protrudes the shaft of the motor, a fan-casing enclosing a fan carried by said shaft and having one of its side-walls provided with a circular opening through which said hub projects, a frusto-conical disc of resilient metal whose central or crown-portion has a circular hole into which the end of said hub extends, means for transmitting to said disc any rotary movement of said fan-casing, and means for exerting friction upon said crown-portion.

4. In combination, in apparatus of the character indicated, a casing containing a motor and having a hub from which protrudes the shaft of the motor, a frusto-conical member whose central or crown-portion is swivelled upon said hub, a second casing carried by the marginal portion of said member and enclosing a fan carried by said shaft, and means exerting friction upon said crown-portion.

In testimony whereof I affix my signature.
ERNEST O. FREDERICKS.
